UNITED STATES PATENT OFFICE.

JOHN C. McLACHLAN, OF CHICAGO, ILLINOIS, ASSIGNOR TO ARNOLD HOENIGSBERGER, OF SAME PLACE.

DITCHING-MACHINE.

SPECIFICATION forming part of Letters Patent No. 380,128, dated March 27, 1888.

Application filed March 14, 1887. Serial No. 230,891. (No model.)

To all whom it may concern:

Be it known that I, JOHN C. McLACHLAN, of Chicago, county of Cook, and State of Illinois, have invented certain new and useful Improvements in a Ditching-Machine, of which the following is a full, clear, and exact description, that will enable others to make and use the same, reference being had to the accompanying drawings, forming a part of this specification.

This invention relates to improvements in that class of machines employed in excavating ditches; and the same consists of certain novel features in the construction, combination, and arrangement of the several parts, as will be hereinafter set forth in detail, and pointed out in the claims.

Figure 1 is a plan or top view of a machine embodying my improved features; Fig. 2, a detached view of the excavating roller or drum. Fig. 3 is a side elevation of that part of the machine carrying the larger end of the excavating-drum; Fig. 4, an elevation of the opposite side; Fig. 5, a vertical transverse section in the plane 5, Fig. 3; Figs. 6 and 7, detached details, and Fig. 8 a rear elevation.

Referring to the drawings, A represents the different timbers forming the supporting framework, A' the main propelling truck-wheels, and A² the front truck or guide wheels located under the engine-platform A³. The rear wheels, A⁴, steady and prevent too much vibration of the excavating-drum, and at the same time assist in supporting the derrick mechanism.

The excavating-drum or hollow roller B is in the form of a conic frustum, (see Fig. 2,) provided on the interior with the central hub, a, and a number of arms, a', (see Fig. 3,) mounted on the shaft a², which is in turn at the larger end of the drum provided with a journal-bearing in the lower end of the double bearing-bracket a³, secured to the frame-work. The opposite end of the shaft a² is supported in double bearings in the projecting frame a⁴, as shown in Figs. 1, 4, 5, and 8.

The excavating-drum and shaft upon which the same is mounted are set on an incline, the degree of inclination being governed by the amount of slope to be given to the sides of

the ditch, the larger end of the drum resting in and cutting out the center and deepest part of the ditch and gradually sloping the sides of the same toward the top in accordance with the contour and inclination of the drum.

55

The excavating-buckets C are rigidly mounted on the periphery of said drum and arranged spirally relative to the circumference of the same, as shown in Figs. 2 and 5. These buckets are arranged in a number of rows disposed at intervals and given a slight degree of spirality or pitch relative to the right line of the drum. The cutting-edges of the buckets C are curved somewhat (see Fig. 7) to facilitate the scooping out of the earth and at the same time to better retain the load. The angle at which the buckets are set together with the incline of the drum causes the same to enter the ground endwise with a shearing cut, thus gradually removing the earth and requiring the least possible power to operate the machine. The excavating-drum rotates in the direction indicated by the arrow, the earth falling or gravitating back onto the endless conveyer B' as the series of buckets reach a certain point above the same.

65

The excavating-buckets are set at some distance apart (see Fig. 6) on the periphery of the drum, and are rounded on the cutting ends, so as to more easily penetrate the earth and do better work than if the buckets were continuous. The lower half or part of the space between the series of buckets is closed by the connecting-plates a⁵, which prevent the earth from passing through, and also serve to stiffen and assist in securing the buckets in place. The buckets are firmly and removably secured to the drum by being bolted to the brackets a⁶, which are in turn bolted to the drum, as shown in Fig. 7. The buckets will be composed ordinarily of steel, and when worn out may be readily removed and replaced by others. The earth is carried along and discharged from the end of the conveyer at one side of the ditch. The inner edge of the grading-leg B² is set very close to the outer end of the conveyer, (see Figs. 1 and 5,) leaving just sufficient space for the passage of the excavated material. The grading-leg carries an endless belt on which are mounted a number of traveling scrapers, a⁷, 75

80

85

90

95

100

which move in the direction indicated by the arrow. These scrapers serve to remove the earth farther away from the ditch, so as to prevent the same from being washed back, and at 5 the same time grade the surface as the work progresses. The apron a^8 prevents the earth from being thrown over the side of the conveyer.

The outer end of the grading-leg B^2 may be 10 raised or lowered to bring the same to any desired angle by means of the turn-buckle b in the supporting brace-rod b' .

The scrapers a^7 are kept in motion by means 15 of the link-belts b^2 , running over the sprocket-wheels b^3 , located at each end of the leg, as shown in Fig. 1. The journal-shafts b^4 b^5 , located in the adjacent ends of the conveyer and grading-leg, have the engaging gear-wheels b^6 b^7 mounted thereon, by which means a simultaneous movement is communicated to both. 20 Power and motion are transmitted from the engine B^3 to these parts through the medium of the engine-shaft B^4 , Fig. 3, sprocket-wheel C' , link-belt C^2 , sprocket-wheel C^3 , main shaft C^4 , Fig. 1, sprocket-wheel C^5 , mounted in the 25 middle of the main shaft, link-belt C^6 , running over sprocket-wheel C^6 and sprocket-wheel C^7 , located directly underneath and mounted on counter-shaft C^8 , as shown in Fig. 3. Mounted 30 on the outer end of the counter-shaft C^8 is the bevel-gear d , which engages with the companion gear d' , mounted on one end of the shaft D , arranged at right angles to the shaft C^8 . The opposite end of the shaft D engages with the conveyer-shaft b^4 , as shown in Fig. 1.

Motion is transmitted from the main or driving shaft C^4 to the excavating-drum by means 35 of the sprocket-wheel D' , mounted on said shaft, link-belt D^2 , sprocket-wheel D^3 , mounted on drum-shaft a^2 , and the pinion d^3 , mounted on said latter shaft, which is adapted to engage with the internal gear wheel or ring, D^4 , rigidly secured to the inside of the drum.

The scraper E is secured to the frame-work 45 and located close to and just back of the excavating-drum. The angular edge of this scraper comes in contact with and levels the sloping surface and at the same time shapes the sides of the ditch.

50 The derrick mechanism F serves the pur-

pose of raising up the excavating-drum out of contact with the ground when transporting the machine from place to place.

Having thus described my invention, what I claim as new, and desire to secure by Letters 55 Patent, is—

1. In a ditching-machine, the combination, with an excavating-drum or roller in the form of a conic frustum and set on an incline, of a series of excavating-buckets arranged in rows 60 encircling the periphery of said drum, said rows being disposed at intervals, substantially as described.

2. In a ditching-machine, the combination, with a conical-shaped excavating-drum, as described, of a series of excavating-buckets arranged upon the periphery of said drum in a number of continuous rows, said buckets having curved cutting-edges and being placed end-wise relative to each other and at right angles, 70 or nearly so, to the axis of the excavating-drum, substantially as set forth.

3. In a ditching-machine, the combination, with the excavating-drum, of the series of buckets C and the connecting-plates a^5 , substantially as and for the purpose set forth.

4. In a ditching-machine, the combination, with the excavating-drum, of a series of excavating-buckets arranged end to end and encircling said drum in rows, and the bracket or 80 brackets a^6 , substantially as set forth.

5. In a ditching-machine, the combination, with the excavating-drum having excavating-buckets mounted on the periphery of the same, of the endless conveyer B' and the grading-leg B^2 , the traveling scrapers a^7 , and the means described for transmitting motion to said conveyer and the grading mechanism, all substantially as and for the purpose set forth.

6. In a ditching-machine, the combination, 90 with a conical excavating-drum, of a series of excavating-buckets arranged spirally upon the circumference of said drum, and with their cutting-edges at right angles to the same, and the scraper E , located back of said drum, substantially as set forth.

JOHN C. McLACHLAN.
